Herman Miller, Inc., Zeeland, Mich., a corporation of Michigan

Filed Feb. 14, 1962, Ser. No. 68,814

Term of patent 14 years

(Cl. D92—26)

FIG. 2.

FIG. 1 is a schematic plan view of the tablecloth, showing the arrangement of the twelve identical sections constituting the entire design; and

FIG. 2 is an enlarged view showing one of the sections enclosed within the dot-and-dash lines, with a section of the plain border outside the circular dot-and-dash line being broken away for convenience of illustration.

I claim:

The ornamental design for a tablecloth, substantially as shown and described.
